UNITED STATES PATENT OFFICE.

JULIUS W. ROGERS, (ADMINISTRATOR OF THE ESTATE OF J. WILBUR ROGERS, DECEASED,) OF WEST MERIDEN, CONNECTICUT, ASSIGNOR TO C. ROGERS & BROTHERS, OF SAME PLACE.

DESIGN FOR COFFIN-HANDLES.

SPECIFICATION forming part of Design No. 11,818, dated June 8, 1880.

Application filed May 3, 1880. Term of patent 7 years.

To all whom it may concern:

Be it known that J. WILBUR ROGERS, deceased, late of West Meriden, in the county of New Haven and State of Connecticut, did invent a new Design for Coffin-Handles; and I do hereby declare the following, when taken in connection with the accompanying drawing and the letters of reference marked thereon, to be a full, clear, and exact description of the same, and which said drawing constitutes part of this specification, and represents a front view of the socket, lever, and one end of the lifting-bar.

This invention relates to a design for handles placed upon the side of coffins for the purpose of lifting them; and it consists in the configuration and ornamentation, as shown in the accompanying illustration.

The socket is of diamond shape with an enlargement at each angle, representing a smaller diamond as intersecting the larger diamond or body. Around the edge and following the lines of the body and the smaller diamond shapes is a plain band or border. On the center of the body is the socket-base A, of corresponding diamond shape, its sides parallel to the sides of the body. The surface between is ornamented by a tracery in relief, and at each angle of the base is a small raised diamond-shaped boss, a, which may serve as a bearing for the screw-heads.

The tip consists of a polygonal base, B, resting on a bead, b. From the end of the base the neck C is contracted, and then expands in

a curve line to a fillet, d; then a section, D, 35 presents an inverted-V-shaped edge, the angle flattened, so as to produce a series of diamond-shaped surfaces around the section D; then a fillet, e, corresponding to the fillet d, thence contracting in a curve line to a section, E, 40 similar to the section D, but smaller, then terminating in a pointed tip, all as shown in the accompanying illustration.

The socket may be used with a different tip, or the tip with a different socket, without departing from this design, it only being essential that with this base there shall be a tip, or with the tip there shall be a base.

I claim—

1. The design for coffin-handle socket, consisting of the diamond-shaped base, with the diamond-shaped enlargements at each angle, the correspondingly diamond shaped base A on the body, the plain border around the body, and enlargements, as shown in the accompanying illustration.

2. The design for coffin-handle tip, consisting of the polygonal base B, the neck C, the inverted-V-shaped sections D and E, with the series of diamond-shaped surfaces at the angle of the said section, all as shown in the accompanying illustration.

JULIUS W. ROGERS,

Administrator of the estate of J. Wilbur Rogers.
